F. C. OVERBURY.
METHOD OF LAYING WATERPROOF ROOFING.
APPLICATION FILED JAN. 3, 1912.

1,102,680.

Patented July 7, 1914.

UNITED STATES PATENT OFFICE.

FREDERICK C. OVERBURY, OF NEW YORK, N. Y., ASSIGNOR TO FLINTKOTE MANUFACTURING COMPANY, OF RUTHERFORD, NEW JERSEY, A CORPORATION OF NEW JERSEY.

METHOD OF LAYING WATERPROOF ROOFING.

1,102,680.

Specification of Letters Patent.

Patented July 7, 1914.

Application filed January 3, 1912. Serial No. 669,224.

To all whom it may concern:

Be it known that I, FREDERICK C. OVERBURY, a citizen of the United States, and resident of New York, in the county of New York and State of New York, have invented certain new and useful Improvements in Methods of Laying Waterproof Roofing, of which the following is a specification.

10 This invention has relation to waterproof and weatherproof roofing and to methods of laying the same.

Prepared weatherproof roofing, as a general rule, consists of sheets of felt or paper 15 saturated with a waterproofing material such as asphalt, pitch or the like, and having a skin coat of harder asphalt or pitch or a mixture thereof. In laying such a roofing, it is highly desirable that there 20 shall be no apertures formed therein in such way as to permit water to leak through to the supporting boards or foundation. Where the strips of roofing are cut with serrated edges to produce a tile or shingle 25 effect when laid, the problem of fastening the points or shingle ends is a difficult one, not only because of the danger of rain leaking through the apertures made by the fastening nails but also because of the liability 30 of the sheet to expand or contract laterally of its length.

The present invention provides a convenient method of laying the roofing material in such way that there are no through apertures, and yet each layer is fastened to the 35 boards or foundation and to the adjacent layers.

On the drawings,—Figure 1 illustrates a portion of a strip of waterproof weatherproof flexible roofing which in this case has a slotted edge to produce a shingle effect when laid. Fig. 2 represents a roof on which the roofing material is partially laid. Fig. 3 shows the same with the free edges 40 of the strips fastened. Fig. 4 is a perspective view on a larger scale, showing the roofing when completely laid and fastened. Figs. 5, 6 and 7 represent cross sections through the roof and illustrate the several 45 steps taken in laying the prepared roofing. Fig. 8 represents an enlarged section on the line 8—8 of Fig. 7. Fig. 9 shows a roof provided with plain and unserrated roofing material. Fig. 10 represents a section on 50 the line 10—10 of Fig. 9.

Briefly stated, the method of laying consists of the following steps, to wit,—laying the strips of roofing material so that each one overlaps at least two of those immediately below it, securing the upper edge of 60 each strip by fastenings directly to the foundation, and then attaching the lower edge of each strip by fastenings to the body of the strip next immediately below it without penetrating the third or lowermost strip. In 65 this way, each strip is attached by nails or like fastenings directly to the boards which constitute the foundation, and its free edge is secured to the next adjacent strip by fastenings, between which and the foundation 70 is an unperforated portion of roofing material. A certain flexibility is thus allowed the laid roofing, and yet the latter is secured so securely in place that high winds, unless extremely violent, will not dislodge or injure it. Where the lower edge of the roofing is slotted or serrated, a fastening may 75 be passed through each shingle or point as shown.

Proceeding to a detailed description of my 80 method of laying a roofing, and assuming that the roofing strip is slotted on one edge, as illustrated in Fig. 1, to produce a shingle effect when laid, I first nail or otherwise secure to the lower edge of the roof or side of 85 a building a strip *a* of roofing material. This strip is laid with its unbroken edge downward and nails or other fasteners as at *a'* are driven through it into the foundation which is conventionally illustrated at *A* as 90 consisting of boards laid edge to edge. Then from the lower edge of the roof or side of the building the roofing strips are laid, one overlapping the one immediately beneath it, about two thirds of its width, so that after 95 the strips are all laid, there will be two thicknesses or portions of strips below the lower edge of each strip, as shown in Figs. 2 and 5. These several strips are indicated at *b c d e f*. The upper edge of each of said strips, which is in contact with the foundation, is tacked or nailed thereto by nails or other fastenings indicated at *b' c' d'*, etc., leaving the lower edges of the several strips 100 free. Then commencing with the upper strip (*e* for instance), the free edge of it and the one immediately below it (*d*) are lifted to receive a metal plate to constitute an anvil, and through the lower edge of the 105 upper strip *e* and the body portion of the 110

next lower strip *d* are passed rivets or other fasteners *e*² to secure them together, after which the anvil is withdrawn. These fasteners, if the lower edge of the strip is serrated, notched or slotted, are passed through the points or projections so that each is fastened down to the body of the strip below it. Then similarly fastenings are passed through the lower edge of the strip *d* and 10 the body of strip *c*, and through the lower edge of strip *c* and body of strip *b*, until the lower edges of all the strips are secured. Through the edge of the strip *b* nails may be driven into the foundation, or the said 15 edge may be fastened by rivets or other fastenings to the strip *a*.

From the foregoing description, taken in connection with the drawings, it will be seen that, although each strip is secured directly 20 to a foundation *A*, the fastenings which effect this are all covered by superimposed overlapping layers of the roofing strips, and that the portions of the strips which underlie the exposed fastenings are imperforate, 25 so that there can be no leakage of rain to the foundation. Any water, which leaks through the apertures in which the exposed fastenings are secured, flows down over the layer beneath such fastenings. The roof or 30 side of the building is covered with three layers of roofing material throughout substantially its entire extent.

It is evident that the roofing strips may have their lower edges cut into any desired 35 conformation to produce, when laid, an ornamental effect. After the strips have all been secured in place, the entire exposed surface of the roof may be covered with a layer of suitable weatherproof and waterproof 40 paint of any desired color, which has the effect of causing the adherence of the exposed overlapping layers and of filling the spaces between the exposed fastenings and the walls of the apertures through which 45 they are passed.

Having thus explained the nature of my said invention and described a way of constructing and using the same, although without attempting to set forth all of the forms

in which it may be made or all of the modes 50 of its use, what I claim is:—

1. The herein described method of laying elongated strips of waterproof and weatherproof flexible material upon a foundation, which consists in overlapping said strips in 55 sequence, securing the upper edge of each strip directly to the foundation, and securing the free edge of each strip to the body of the next lower strip by fasteners which are located above an unperforated body portion 60 of an underlying third strip.

2. A roof or siding comprising a foundation, a plurality of strips of prepared flexible weatherproof waterproof material arranged with each strip overlapping two adjacent lower strips, fasteners securing the upper edge of each strip directly to said foundation, fasteners passed through the lower edge of each strip and through the body of the next overlapped lower strip 70 without penetrating the third overlapped strip.

3. A roof or siding comprising a foundation, a plurality of layers of waterproof material each having an edge formed with 75 projections, said layers being arranged with each layer overlapped by two superimposed layers and with each layer having at its exposed lower edge portion said projections, fastening securing the upper edge of each 80 layer to the foundation, and fasteners located above the body of each lower layer and securing together the body and the projections of the lower edge portion respectively of the two superimposed layers, so 85 that the projections of the exposed edge portion of each layer are secured by fasteners to the body portion of the layer immediately beneath it with an unperforated portion of the lowest layer below the fastener.

In testimony whereof I have affixed my signature, in presence of two witnesses.

FREDERICK C. OVERBURY.
